(57) **CLAIM**

The ornamental design for a flexible landscape edging, as shown and described.

DESCRIPTION

FIG. 1 is a right side perspective view of a flexible landscape edging, showing my new design;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof; and,

FIG. 8 is an enlarged cross-sectional view taken along line 8-8 in FIG. 2.

The broken line showing of the flexible landscape edging is for the purpose of illustrating a hole and forms no part of the claimed design.
